FACING MACHINE FOR VALVES AND TIMERS

Filed March 16, 1927

INVENTOR.
GLEN N. KROUSE

BY *Albert C. Bell*

ATTORNEY.

UNITED STATES PATENT OFFICE.

GLEN N. KROUSE, OF VALPARAISO, INDIANA.

FACING MACHINE FOR VALVES AND TIMERS.

Application filed March 16, 1927. Serial No. 175,741.

My invention relates to an improved device for facing the contacts of timbers employed, for example, on motor vehicles and for also facing the valves of internal combustion motors. My improved facing machine is intended primarily to permit anyone owning a motor vehicle or having occasion from time to time to face timers and valves, to have a device that will do this work simply and effectively, and this I accomplish by constructing the device in a simple manner for hand operation, so that the same machine will face a timer and valves of different sizes, without requiring a large number of expensive parts to secure the intended result. My improved facing machine is applicable particularly to standard timers used on Ford motor vehicles and to face the valves of the different sizes used in Ford passenger cars and tractors, although the same kind of construction and operation may be employed with any timers of the same general design and with valves of any size and kind.

My invention will best be understood by reference to the accompanying drawings showing a preferred embodiment thereof in which

Fig. 1 is a vertical, central, sectional view through the cutter shaft of the device, and shows a timer shell in place on the device,

Fig. 2 shows in a view similar to Fig. 1 a valve in position for facing and the auxiliary cutter used for that purpose,

Fig. 3 is a sectional view of the parts shown in Fig. 2 taken along the line 3—3, with the valve removed, and

Fig. 4 is a sectional view to an enlarged scale, of the cutter head shown in Fig. 1 taken along the line 4—4.

Similar numerals refer to similar parts throughout the several views.

As shown in Fig. 1 my device consists of a frame 10 having two bearings 11, 11 to receive a rotary hollow shaft 12 which has rigidly secured to one end a cutter head 13 adjacent a work supporting face 14 perpendicular to the axis of the shaft 12. The cutter head 13 has extending laterally through it, a hole for receiving a cutter bar 15, the lower end of which is provided with a cutting edge 16. As indicated in Fig. 4, the cutter bar 15 is slotted from its upper end to a point adjacent the inserted cutter point 16, to receive the flat wedge shaped end 17 of a rod 18 extending through the

shaft 12 and having a threaded end engaged by a wing nut 19. Around the cutter bar 15 between the cutter head 13 and a pin 20 extending through the upper end of the cutter bar, a spring 21 is disposed, pressing the cutter bar upwardly against the lower inclined surface of the wedge 17. As a result of this, the spring 21 tends to move the cutter point 16 away from the work, as far as the wedge 17 will permit, and to secure a desired amount of cutting action, the nut 19 is turned relatively to the shaft 12, until the wedge 17 forces the cutter bar 15 towards the work enough to take the desired cut when the shaft 12 is rotated. A handle 22 is secured to the outer end of the shaft 12 by a clamping bolt 23 to rotate the shaft 12 as desired.

To conveniently center a timing shell 24 coaxially with the axis of the shaft 12, the face 14 is provided with shouldered grooves 25, substantially fitting the edge of the timer shell. A yoke 26 extends around the shell 24 to hold it in place in the grooves 25, the ends of the yoke extending as indicated in Fig. 3, through opposite sides of the face 14 of the frame, where they are engaged by thumb nuts 27.

It will be observed that the shaft 12 is longer than the overall dimension of the bearings 11, 11, and this permits sufficient axial motion of the shaft to move the cutter entirely across the contacts of the timer during a facing operation. In order that the device may be of simple and inexpensive construction, I avoid mechanical devices for securing this axial motion in any way, and find that good results may be secured by exerting a small amount of friction on the shaft 12 to prevent it moving freely. When this friction is exerted on the shaft, a turning movement of the handle 22 is easily and readily combined with the requisite amount of pressure axially of the shaft 12 to feed the cutter across the face of the timer contacts.

By using a little care in the operation and taking a light cut each time, the timer contacts may readily be faced with quite as good results as could be secured in a power machine. I find it convenient to produce the requisite friction on the shaft 12, by means of a flat spring 28 secured to a web 29 of the frame and resting with a small amount of spring action against the side of the shaft 12 between the bearings 11, 11.

As indicated in Fig. 3, I prefer to cut away the face 14 as indicated at 30, 30, to provide sight openings to inspect the inside of the timer shell during a facing operation, to the end that the shell need not be removed from the device until the facing is completed. To conveniently support the machine, I extend the frame 10 into jaws 31, 32, through the lower one of which I extend a clamping screw 33 so that any desired supporting surface may readily be clamped between the jaw 31 and the screw 33.

Referring to Fig. 3, it will be observed that besides the bearings 11, 11, other bearings 34 and 35 are provided in the frame, these bearings being in pairs as indicated for the bearings 35 in Fig. 2, to receive valve stems of different size valves. Below the bearings 34 and 35, the face 14 is provided with an aperture 36 to receive a chuck 37, which in turn holds a cutter bar 38, ground at its end at the proper angle to face the valve surface 39 of the valve carried by the valve stem 40. The valve stem 40 extends beyond the bearings 35 and is engaged by a second aperture in the handle 22 which is clamped to the valve stem by the clamping bolt 23, it being understood that the handle is split sufficiently so that the single clamping screw 23 will clamp either the shaft 12 or a valve stem as desired. By rotating the valve for the relation of the parts indicated in Fig. 2, by means of the handle 22, the valve face 39 may be faced by the cutter 38 so that a true valve surface is again had after the valve has become worn in use. The facing or truing of a valve of different size mounted in the pair of bearings 34 is similarly accomplished. I find it convenient to shape the web 41 so that its outer edge consists of plane surfaces 42 and 43 intersecting each other at the angle to which the end of the cutter 38 should be ground relatively to the side of the cutter, and said plane surfaces 45 form a convenient gauge for grinding the cutter by applying it to the web 41 as indicated in dotted lines at 44 in Fig. 2. The cutter 38 may readily be given any desired adjustment by loosening the nut 45 of the chuck 37, for which condition the cutter may be rotated or moved longitudinally in the chuck as desired, and by removing the nut 45, the chuck may readily be removed from the frame 10.

From the above it will be observed that my facing machine provides a convenient means for accomplishing the intended results, that the only parts required to face the valves in addition to facing the timers, are the chuck and the cutter bar carried by it, and that the machine may conveniently be constructed to face valves of different kinds and sizes. Furthermore my machine is inexpensive in construction and affords a ready means for avoiding the delays and expense

incident to taking timer shells and valves to a place where power machinery is available for facing them.

While I have shown my invention in the particular embodiment above described, it will be understood that I do not limit myself to this exact construction as I may employ equivalents known to the art at the time of the filing of this application without departing from the scope of the appended claims.

What I claim is:

1. In a facing machine for valves and timers, the combination of a frame having bearings, a tubular shaft rotary in said bearings and movable longitudinally therein, a cutter head carried by one end of said shaft and having a laterally extending hole therethrough, a slotted cutter bar in said hole, a feed bar extending through said shaft and threaded at one end and at the other extending into an outwardly diverging wedge portion in the slot of said cutter bar, a feed nut on the threaded end of said feed bar adjacent the end of said shaft, a handle on said shaft for turning it, said frame having a work supporting face perpendicular to said shaft adjacent said cutter head for receiving a timer shell, and clamping devices for holding a timer shell on said face around said cutter head.

2. In a facing machine for valves and timers, the combination of a frame having bearings, a tubular shaft rotary in said bearings and movable longitudinally therein, a cutter head carried by one end of said shaft and having a laterally extending hole therethrough, a slotted cutter bar in said hole, a feed bar extending through said shaft and threaded at one end and at the other extending into an outwardly diverging wedge portion in the slot of said cutter bar, a feed nut on the threaded end of said feed bar adjacent the end of said shaft, a handle on said shaft for turning it, said frame having a work supporting face perpendicular to said shaft adjacent said cutter head for receiving a timer shell, clamping devices for holding a timer shell on said face around said cutter head, and friction means restraining said shaft against free movement.

3. In a facing machine for valves and timers, the combination of a frame having bearings, a tubular shaft rotary in said bearings and movable longitudinally therein, a cutter head carried by one end of said shaft and having a laterally extending hole therethrough, a slotted cutter bar in said hole, a feed bar extending through said shaft and threaded at one end and at the other extending into an outwardly diverging wedge portion in the slot of said cutter bar, a feed nut on the threaded end of said feed bar adjacent the end of said shaft, a handle on said shaft for turning it, said frame having a work supporting face perpendicular to said

shaft adjacent said cutter head for receiving a timer shell, clamping devices for holding a timer shell on said face around said cutter head, and a spring holding said cutter bar 5 against said wedge portion.

4. In a facing machine for valves and timers, the combination of a frame having bearings, a tubular shaft rotary in said bearings and movable longitudinally therein, a cutter head carried by one end of said shaft and having a laterally extending hole therethrough, a slotted cutter bar in said hole, a feed bar extending through said shaft and threaded at one end and at the other extending into an outwardly diverging wedge portion in the slot of said cutter bar, a feed nut on the threaded end of said feed bar adjacent the end of said shaft, a handle on said shaft for turning it, said frame having a work supporting face perpendicular to said shaft adjacent said cutter head for receiving a timer shell, clamping devices for holding a timer shell on said face around said cutter head, said face having a circular shoulder coaxial with said shaft for receiving and centering the edge of a timer shell.

5. In a facing machine for valves and timers, the combination of a frame having bearings, a tubular shaft rotary in said bearings and movable longitudinally therein, a cutter head carried by one end of said shaft and having a laterally extending hole therethrough, a slotted cutter bar in said hole, a feed bar extending through said shaft and threaded at one end and at the other extending into an outwardly diverging wedge portion in the slot of said cutter bar, a feed nut on the threaded end of said feed bar adjacent to the end of said shaft, a handle on said shaft for turning it, said frame having a work supporting face perpendicular to said shaft adjacent said cutter head for receiving a timer shell, and clamping devices for holding a timer shell on said face around said cutter head, said face being cut away to afford a sight opening permitting inspection of the interior of a timer shell during a facing operation.

6. In a facing machine for valves and timers, the combination of a frame having 50 bearings, a tubular shaft rotary in said bearings and movable longitudinally therein, a cutter head carried by one end of said shaft and having a laterally extending hole therethrough, a slotted cutter bar in said hole, a feed bar extending through said shaft and threaded at one end and at the other extending into an outwardly diverging wedge portion in the slot of said cutter bar, a feed nut 55 on the threaded end of said feed bar adjacent the end of said shaft, a handle on said shaft for turning it, said frame having a work supporting face perpendicular to said shaft adjacent said cutter head for receiving a timer shell, clamping devices for 60 holding a timer shell on said face around said cutter head, said frame having extending jaws below said face, and a clamping screw through one of said jaws for clamping a supporting member against the other of 65 said jaws.

7. In a facing machine for valves and timers, the combination of a frame having bearings, a tubular shaft rotary in said bearings and movable longitudinally therein, a 75 cutter head carried by one end of said shaft and having a laterally extending hole therethrough, a slotted cutter bar in said hole, a feed bar extending through said shaft and threaded at one end and at the other extending into an outwardly diverging wedge portion in the slot of said cutter bar, a feed nut 80 on the threaded end of said feed bar adjacent the end of said shaft, a handle on said shaft for turning it, said frame having a work supporting face perpendicular to said shaft adjacent said cutter head for receiving a timer shell, clamping devices for holding a timer shell on said face around said cutter head, a spring retainer on the slotted end 85 of said cutter bar, and a spring between said retainer and said head holding said cutter bar against said wedge portion.

In witness whereof, I hereunto subscribe my name this 12th day of March, A. D. 1927.

GLEN N. KROUSE.
